LID SUPPORT FOR CEDAR CHESTS

Grady A. Loftin, Altavista, Va., assignor to The
Lane Company, Inc., a corporation of Virginia

Application September 15, 1933, Serial No. 689,676

6 Claims. (Cl. 217—60)

This invention relates to improvements in cedar chests and like storage receptacles, and has particular reference to the provision of a novel and improved support for holding the chest lid or cover in open position.

Heretofore lid supports of the type to which my invention relates have been arranged and mounted, that is, connected to the chest body and lid or cover, so as to be exposed on the inside of the chest when the lid or cover is in closed position. Supports of this type, besides being objectionable because of the liability of the clothes becoming entangled therewith and causing damage either to clothes or the support, or both, are also open to other material objections. These supports, usually in the form of hinged stay members, are commonly made of a metal or metals which, like the other hardware elements of the chest, are attractive to cedar oil aroma or vapor and, as a result, cedar oil deposits are caused thereon in the form of a gummy coating which is liable to stain and otherwise cause injury to the clothes or other contents of the chest. It has been discovered that such deposits on hardware fittings due to catalytic action can be overcome by making the metal parts of metal or metal alloys which are non-catalytic or non-attractive to cedar oil vapor or by providing the metal parts with a coating or plating of such non-catalytic metals or alloys. For purposes of economy it is desirable, of course, to use hardware fittings plated in this manner, but this can not be done without detriment in the use of inside stay supports, for the reason that the rubbing action of the relatively hinged component parts of such supports on one another causes wear and a scraping away of the plating leaving the catalytic metal exposed. Furthermore, the elements of the inside type supports heretofore used are, when the lid or cover is closed, disposed upon the inside of the chest so as to be fully exposed to the action of the cedar oil vapor, so that, in case of the exposure of catalytic metal surfaces, a rapid gumming thereof through the action of the deposit of cedar oil thereon will occur.

One object of my invention is to provide a construction of lid support which adapts the parts to be so mounted upon the chest body and lid that when the lid is closed the parts of the lid support will lie in substantially parallel relation and horizontally or substantially so between the sides of the lid and sides of the body and on the outside of the walls of the latter, so as to be fully protected from any action or deposits of cedar oil vapor thereon and at the same time obviate any

liability of contact between the parts of the support and the clothing or other contents of the chest.

Another object of the invention is to provide a construction and arrangement of the parts of the support whereby said parts are adapted to relatively fold in a compact manner between the chest body and the lid when the latter is closed.

Still another object of the invention is to provide a construction and arrangement of the support parts and mode of mounting the same upon the chest body or lid whereby the use of non-catalytic metal may be avoided, if desired, and whereby a more presentable type of support is furnished, suitable for use upon fine chests, and also whereby an arrangement is obtained which avoids liability of injury to the parts of the chest by the working action of the parts of the support.

With these and other objects in view, the invention consists of the features of construction, combination and arrangement of parts, hereinafter fully described and claimed, reference being had to the accompanying drawings, in which:

Fig. 1 is a perspective view of a cedar chest provided with a lid support embodying my invention and showing the lid supported in open position thereby.

Fig. 2 is a view in side elevation of the chest with the lid closed and partly broken away to show the parts of the support at the side thereof which is in view.

Fig. 3 is a section on line 3—3 of Fig. 1.

Fig. 4 is a section similar to that shown in Fig. 3 with the lid in closed position.

Fig. 5 is a vertical section on line 5—5 of Fig. 2.

Fig. 6 is a horizontal section on line 6—6 of Fig. 4.

In the accompanying drawings I have shown the application of my invention to a cedar chest 1 of usual type comprising a body 2, usually of rectangular or oblong rectangular form, and a hinged lid or cover 3. This lid or cover 3 is provided on its underside with a resilient metallic sealing strip 4, of the type used upon the well known Lane chest, for engagement with the upper marginal edges 5 of the front, rear and end walls 6, 7 and 8, respectively, of the chest to close the joint between the chest and lid when the latter is in closed position so as to prevent the escape of cedar oil aroma or vapor to the atmosphere.

The front, rear and end walls 6, 7 and 8 of the chest body and the bottom wall 9 thereof are formed of cedar oil bearing wood and provided each with an outer veneer 10 of mahogany,

walnut or other desired finishing wood. This veneer is preferably coated with varnish or a similar preservative and decorative coating 11 which terminates a predetermined distance below the marginal wall edges 5, leaving a plain surface 12 along the top portion of each wall which is unvarnished or free from the coating material. At the base of such surface 12 is a groove 13 which separates the uncoated zones 10 from the coated zones of the walls. The purpose of employing the bare or uncoated wall zones 12 is to enable the walls 6, 7 and 8 to be coated by spraying or otherwise with the varnish or coating material without liability of any of such 15 material being sprayed into the chest body and spotting or otherwise coating the internal aroma exudation surfaces thereof. By this means such surfaces are left exposed for the free and unimpeded exudation of the cedar oil aroma, and at 20 the same time the walls are protected from being coated by the varnish or coating material which would not only interfere with the free exudation of the vapor but, as such substances are attractive to cedar oil, would cause the undesirable formation of gummy spots on the inner 25 surfaces of the chest walls.

The lid or cover 3, as shown, is connected at its rear edge by hinge members 14 to the rear wall of the chest body, and said lid or cover is 30 provided on its underside with molding strips forming depending front and side walls 15 and 16, respectively, which extend downwardly on the outside of the upper portions of the walls 6 and 8 of the body 2 when the lid or cover is in closed 35 position, in which position the portion of the resilient sealing strip 4 engage the marginal edges of the walls 6, 7 and 8 of the body. The chest may be provided with a latch or lock of suitable type to hold the lid in closed position, said 40 latch or lock comprising engaging and keeper members 17 and 18 upon the lid and front wall of the chest body. These lock parts as well as the hinge members and other hardware fittings of the chest are preferably in practice made 45 either of non-catalytic metal or provided with a plating or coating of non-catalytic metal or material in order to protect the same from the accumulation of cedar oil vapor in the form of a gummy deposit thereon due to catalytic action.

50 The support comprising the present invention for holding the lid 3 in open position comprises a pair of supporting members at each side of the chest, each pair of supporting members consisting of a guide member or strip 19 on the lid 55 and a stay link 20 slidably connecting the same with the chest body. Each guide strip 19 is formed of metal of suitable stiffness arranged to bear against the inner face of the adjacent depending side wall of the lid 3 or a molding strip secured thereto and said guide strip is provided at its opposite ends with perforations 21 for the passage of securing screws or the like to secure it in position. Between these perforations the strip is formed with a longitudinally extending 60 guide slot 22, said slot cooperating with a groove 23 formed in the side wall or molding strip 16 to form a guideway. The coacting stay link member 20 is secured at one end by a pivot pin or screw 24 to the adjacent wall 8 of the chest body and is provided at its opposite end with a headed pin or stud 25 which is arranged to travel in the guideway 23 to slidably and pivotally connect the link member with the lid or cover 3. The arrangement of these parts is such 65 that when the lid 3 is fully open and disposed

in a direct vertical position, the links 20 will lie at an upward and rearward angle with the studs 25 positioned at the rear ends of the slots 22, in which position the links will hold the lid against backward movement and against forward movement unless pressure is applied thereto. By positively moving the lid 3 forwardly and downwardly from its open position the links 20 will be caused to swing forwardly therewith on their pivots 24 to a certain degree, after which the pins or studs 25 will slide forwardly in the guide slots 22 to allow the lid to have free downward movement to closed position, in which movement the guide strips and links will fold into parallel relation so as to lie between the uncoated portions of the sides 8 of the chest body and the depending sides 16 of the closed lid.

80 It will be understood from the foregoing that the novel construction and arrangement of the slotted guide strips and links permit of such 85 location and movements of the support members, whereby the parts of the supports will be exposed only when the lid is open and will be disposed on the outside of the chest body and concealed and protected from contact with the aroma 90 or vapor in the chest at all times when the cover is closed. By this means the support members will be so placed that they can not interfere with the clothing or contents of the chest so as to be injured by contact therewith or to cause 95 injury to such contents. Also it will be seen that the supporting members by being sealed against exposure to the atmosphere of the chest will be protected against the deposit of cedar oil vapor by catalytic action thereon, so that the 100 support elements may, if desired, be made without detriment of catalytic metal. Further, in the event that the support members are made of catalytic metal, provided with a plating or coating of non-catalytic material, any rubbing action 105 between them causing such plating or coating to be scraped off would not cause damage to the contents of the chest, as the support elements are at all times so located as to be out of contact therewith.

110 It will be observed that these important advantages are obtained by constructing and mounting the stay links 20 and their guide strips or plates 19 so that said links and plates or strips relatively fold substantially horizontally and in 115 parallel relation on the outer sides of the wall 6 of the chest body and between the same and the depending sides 16 of the lid so that the supports will lie between the same and be thereby 120 guarded against injury and shielded from exposure 125 either on the inside or the outside of the chest. These advantages are gained in a very simple manner without the necessity of specially constructing the walls of the chest or walls of the lid 130 to provide for the reception of the links, and without adding in any material way to the cost of construction of the chest.

135 From the foregoing description, taken in connection with the drawings, the construction, mode of operation and advantages of my improved support for the lids of cedar chests will be readily understood and appreciated by those versed in the art without a further and extended description. While the construction shown for carrying 140 the invention into practical effect is preferred, it will, of course, be understood that changes in the form, proportion and details of construction may be made within the scope of 145 the invention defined by the appended claims 150

without departing from the spirit or sacrificing any of the advantages thereof.

What I claim is:

1. In a lid support for cedar chests, and in combination with a chest body and its hinged lid, said lid having depending sides arranged to close down upon the outer sides of the sides of the body, guide members disposed upon the inner faces of said depending sides of the lid, and longitudinally straight stay links pivotally connected at one end to the outer faces of the sides of the chest body and slidably and pivotally connected at their opposite ends to the said guide members so as to fold with said guide members substantially horizontally and in parallel relation to each other in the space between the sides of the body and sides of the lid and so as to lie between the upper edges of the sides of the lid in the closed position of the latter. 80
2. In a lid support for cedar chests, and in combination with a chest body and its hinged lid, said lid having depending sides arranged to close down on the outer sides of the sides of the body and provided with grooves upon their inner faces, slotted guide strips secured to said inner faces of the sides of the lid with their slots coacting with the grooves to form guideways, headed pins slidably and pivotally engaging said guideways, and longitudinally straight stay links pivotally connected at one end to the outer faces of the sides of the chest body and connected at their opposite ends to said headed pins so as to fold with said guide strips in parallel relation to each other in the space between the sides of the body and sides of the lid and so as to lie between the upper edges of the sides of the body and the lower edges of the sides of the lid in the closed position of the latter. 85
3. In a lid support for cedar chests, and in combination with a chest body and its hinged lid, said lid having depending sides arranged to close down upon the outer sides of the sides of the body, guide members upon the inner faces of the depending sides of the lid, and longitudinally straight link members pivotally connected to the outer faces of the sides of the body and slidably and pivotally connected at their opposite ends to the guide members, the arrangement being such that in the closed condition of the lid said members and links lie folded substantially in a horizontal plane and in parallel relation in the spaces between the lid and body sides and between the upper edges of the body sides and the lower edges of the sides of the lid on the outside of the body. 90
4. In a lid support for cedar chests, and in combination with a chest body having side walls provided on their outer sides with a finishing coating terminating below their upper marginal edges and leaving uncoated portions between such coated portions and such edges, and a lid having depending sides arranged to close down on the outer sides of the sides of the body, guide members on the inner faces of the depending sides of the lid having longitudinal guideways, and longitudinally straight stay links pivoted at one end upon said uncoated portions of the sides of the body and having their opposite ends slidably and pivotally engaging said guideways of the guide members, said links and members being arranged to fold in a substantially horizontal plane and in parallel relation to each other in the spaces between the sides of the lid and sides of the body and between the upper edges of the body sides and the lower edges of the sides of the lid in the closed position of the lid. 95
5. In a lid support for cedar chests, and in combination with a chest body and its hinged lid, said lid being hinged at its rear edge to the rear edge of the body and adapted to close down upon the upper edge of the body and provided at its front and sides with molding strips adapted to extend outside of and surround the front and side walls of the body when the lid is closed, longitudinally slotted guide members disposed on the inner faces of the side molding strips, and longitudinally straight stay links pivoted to the side walls of the chest body and slidably and pivotally engaging the slots in said guide members so as to fold substantially horizontally parallel with said guide members wholly between the side molding strips and sides of the chest and between the upper edges of the sides of the chest body and lower edges of the sides of the lid when the lid is in closed position. 100
6. In a lid support for cedar chests, the combination, with a chest body, of a hinged lid adapted to close down upon the upper edges of the walls of the body, said lid being provided on its underside at the front and sides with molding strips arranged to lie on the outside of the front and side walls of the body when the lid is in closed position, the molding strips at the sides of the lid having recesses formed in their inner faces, guide plates secured to said side molding strips over said recesses and provided with longitudinal slots 110 cooperating with said recesses to form guideways, headed pins slidably and pivotally engaging the slots in the guide plates and movable in said guideways, and longitudinally straight guide links pivotally connected at one end to fixed pivots on the outer faces of the sides of the chest body and connected at their other ends to said headed pins, the arrangement being such that said links are adapted to fold with said guide plates horizontally in parallel relation to each other in the spaces between the sides of the body and the side molding strips of the lid and between the upper edges of the sides of the body and lower edges of said side molding strips in the closed position of the lid. 115
7. In a lid support for cedar chests, the combination, with a chest body, of a hinged lid adapted to close down upon the upper edges of the walls of the body, said lid being provided on its underside at the front and sides with molding strips arranged to lie on the outside of the front and side walls of the body when the lid is in closed position, the molding strips at the sides of the lid having recesses formed in their inner faces, guide plates secured to said side molding strips over said recesses and provided with longitudinal slots 120 cooperating with said recesses to form guideways, headed pins slidably and pivotally engaging the slots in the guide plates and movable in said guideways, and longitudinally straight guide links pivotally connected at one end to fixed pivots on the outer faces of the sides of the chest body and connected at their other ends to said headed pins, the arrangement being such that said links are adapted to fold with said guide plates horizontally in parallel relation to each other in the spaces between the sides of the body and the side molding strips of the lid and between the upper edges of the sides of the body and lower edges of said side molding strips in the closed position of the lid. 125
8. In a lid support for cedar chests, the combination, with a chest body, of a hinged lid adapted to close down upon the upper edges of the walls of the body, said lid being provided on its underside at the front and sides with molding strips arranged to lie on the outside of the front and side walls of the body when the lid is in closed position, the molding strips at the sides of the lid having recesses formed in their inner faces, guide plates secured to said side molding strips over said recesses and provided with longitudinal slots 130 cooperating with said recesses to form guideways, headed pins slidably and pivotally engaging the slots in the guide plates and movable in said guideways, and longitudinally straight guide links pivotally connected at one end to fixed pivots on the outer faces of the sides of the chest body and connected at their other ends to said headed pins, the arrangement being such that said links are adapted to fold with said guide plates horizontally in parallel relation to each other in the spaces between the sides of the body and the side molding strips of the lid and between the upper edges of the sides of the body and lower edges of said side molding strips in the closed position of the lid. 135
